UNITED STATES PATENT OFFICE.

CHARLES E. WHITTLESEY, OF NEW HAVEN, CONNECTICUT, ASSIGNOR OF ONE-HALF TO HENRY T. PECK, OF SAME PLACE.

LOCK.

SPECIFICATION forming part of Letters Patent No. 320,521, dated June 23, 1885.

Application filed February 4, 1885. (Model.)

To all whom it may concern:

Be it known that I, CHARLES E. WHITTLESEY, a citizen of the United States, residing at New Haven, in the county of New Haven and State of Connecticut, have invented a new and useful Door-Lock, of which the following is a specification.

My invention relates to a new and improved door-lock, and has for its object to provide a lock adapted to bolt and unbolt only by a peculiar and methodical movement of the key.

The invention consists, essentially, of reciprocal bolts arranged and operated as herein-after more fully described and claimed.

In the drawings, Figure 1 is an elevation of my improved lock with the face-plate removed, showing the interior. Fig. 2 is a section of Fig. 1 on the line $x x$. Fig. 3 is an elevation of the interior of the lock, showing the parts locked. Fig. 4 is a section on the line $x x$ of Fig. 3. Fig. 5 is an elevation of the interior, showing the parts unlocked. Fig. 6 is a view of the cylinder. Fig. 7 is a view of the spindle, and Fig. 8 is a view of the spring.

A represents the case of the lock, of ordinary box form, secured at one end to a flange, B, by which it is fastened to the door as a mortise-lock.

A flat plate, C, forms a cover for the case, and is held together by means of a screw fitting a threaded perforation in a projection, d, raised on the case.

Arranged lengthwise within the case are two bolts, e e', of the same length as the case and placed parallel to each other. One of the bolts is located above and the other below the center of the case, and each is cut away on the side toward the center, so as to leave a space between them. On the inner side of each bolt V -shaped notches f f' are formed. The notches are in the same relative position in their respective bolts, and are thus opposite to each other.

For a purpose hereinafter set forth the upper bolt, e, is cut away around the notch f, as shown by the dotted line g, so that in this part the bolt is thinner than the lower bolt; but in every other respect the two bolts are of like dimensions.

Arranged in the space between the bolts is

a perforated cylinder, h, the ends of which bear in corresponding round holes, k k, in the case A and its cover C.

Diametrically opposite on the periphery of the cylinder h are arms l l', which are received in the notches f f' in the bolts.

It is evident that the cylinder h, with its two opposite arms l l', forms a lever fulcrumed at its center and engaged at its ends with the bolts.

The perforation in the cylinder is rectangular, and receives a similar-shaped bar or spindle, m, by which the cylinder is turned.

On that side of the lock intended for the outside when in the door the spindle m is made flush with the end of the cylinder, and has two radial projections, n n, which fit corresponding grooves or notches, n' n', in the cylinder, and prevent the spindle from being pushed through the cylinder from that side. On the opposite side of the lock the spindle projects sufficiently to receive an ordinary door-knob.

There is a key-slot, P, in that end of the spindle which is flush with the end of the cylinder. The key-slot, as shown, is a simple straight slot; but it is evident that it may be formed in various intricate shapes, requiring corresponding complex keys.

On the side of the case A is fastened a spring, r, of the form shown. The annular part of the spring encircles the cylinder and bears against the arms or teeth l l', and presses the cylinder toward the cover of the case.

The arms l l' are not as wide as the space between the lock-case and its cover, and the cylinder can move correspondingly across the case.

The spring r throws the arms against the cover of the case, and pressure on a key inserted in the key-slot P pushes the cylinder toward the back of the case.

The surface of the upper bolt, e, is cut away on the side toward the back of the case, and is not as thick as the bolt e'. Pressure on the key throws the arm l out of the notch f and disengages the arm from the bolt.

Constructed as above described, the operation of my lock is as follows: As the key is turned in either direction, one of the bolts e e' is thrust out and the other withdrawn, and

the door remains bolted; but when the key is pressed sufficiently the cylinder is pushed toward the back of the case, and the arm *l* is depressed and swings under the bolt *e*.

5 To unlock the door, the bolt *e* is first thrust out. The cylinder is then pressed toward the back of the case, disengaging the arm *l* from the bolt *e*. Movement of the key in the opposite direction, pressure being meanwhile exerted on the key, thrusts out the bolt *e'*, and the door is locked by both bolts. Turning the key without pushing the cylinder back thrusts one bolt out and draws the other in, but does not unlock the door.

15 To unlock the door, the bolt *e* may be first withdrawn and the arm *l* then disengaged from the lock, when the reverse motion of the key withdraws the bolt *e'*, and the door is unlocked.

What I claim as new, and desire to secure by 20 Letters Patent, is—

1. In a door-lock, the combination, with a

cylinder, *h*, journaled in spring-bearings in the case and having two opposite radial arms, *l l'*, of parallel bolts engaging therewith, said cylinder adapted to move lengthwise in its 25 bearings, thereby disengaging one of the arms from the bolt it operates, in the manner substantially as described.

2. In combination with the case of a door-lock, a journaled cylinder, *h*, having two opposite radial arms, *l l'*, two parallel bolts, *e e'*, having notches for engaging the arms of the cylinder, a spring, *r*, adapted to maintain the arm *l* in engagement with its corresponding bolt, and the spindle *m*, all arranged and operated in the manner and for the purpose described. 30 35

CHARLES E. WHITTLESEY.
